CLAIM

The ornamental design for a lighting fixture with top mount, as shown and described.

DESCRIPTION

FIG. 1 is a front top perspective view of a lighting fixture with top mount.

FIG. 2 is a front bottom perspective view of the lighting fixture of FIG. 1.

FIG. 3 is a front elevation view of the lighting fixture of FIG. 1.

FIG. 4 is a rear elevation view of the lighting fixture of FIG. 1.

FIG. 5 is a right-side elevation view of the lighting fixture of FIG. 1, a left-side elevation view being a mirror image.

FIG. 6 is a bottom plan view of the lighting fixture of FIG. 1; and,

FIG. 7 is a top plan view of the lighting fixture of FIG. 1.

The broken lines are provided for illustrated purposes only and form no part of the claimed design.
